UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A HANDLE FOR SPOONS.

SPECIFICATION forming part of Design No. 24,536, dated August 13, 1895.
Application filed June 26, 1895. Serial No. 554,140. Term of patent 7 years.

To all whom it may concern:

Be it known that I, CHARLES C. WIENTGE, of Providence, in the county of Providence and State of Rhode Island, have invented and produced a new and original Design for the Handles of Spoons and Similar Articles, of which the following is a specification, reference being had to the accompanying drawings, forming part thereof.

10 Figure 1 represents an obverse view of a handle, illustrating my new design and shown as attached to the bowl of a spoon, the tine portion of a fork being dotted in position. Fig. 2 represents a reverse view of the handle and spoon-bowl.

The essential characteristics of my new design for handles of spoons and similar articles consist in the design as herein shown and described.

20 In the drawings, 5 represents the handle, and 6 the bowl portion, of a spoon, to which the handle is attached. It may, however, represent any similar article. The outline of the handle extends from 7 7 in regular curves,

25 which first suddenly contract the width of the handle to 8 8, then gradually spread outward to increase the width of the handle to 9 9, and, finally, in a succession of short curves over the upper end of the handle. On the obverse

30 the surface ornamentation consists of the line-borders 10 10, which follow the outline of the handle to 9 9, being overlapped by portions

of the inwardly-extending foliations 11 11, forming the upper ends of the inner lines 12 12. Above these foliations 11 11 and within 35 the borders 10 10 are beaded inner borders 13 13 at each side of the convex panel 14, divided at its upper portion into three branches, which are ornamented with scrolled foliations 15 15, arranged in trefoil series. On the reverse 40 the surface ornamentation consists of the scrolled and foliated ornament 16, extending onto the body of the article to which the handle is attached, the double-line borders 17 17 following the outline of the handle 45 from 7 7 to 9 9, the panel 18 having its upper portion divided into branches and the scrolled foliations 19 19 accentuating these branches to form a trefoil ornament.

What I claim is—

50 1. In the design for the handle of a spoon or similar article, the obverse as herein shown and described.

2. In the design for the handle of a spoon or similar article, the reverse as herein shown 55 and described.

3. The design for the handle of a spoon or similar article as herein shown and described.

In witness whereof I have hereunto set my hand.

CHARLES C. WIENTGE.
